MEANS FOR APPLYING LIQUID

Frederick J. Williams, Bellaire, N. Y., and Harmon Howorth, Cumberland, Md., assignors to Celanese Corporation of America, a corporation of Delaware

Application March 26, 1932, Serial No. 601,352

5 Claims. (Cl. 8—19)

This invention relates to method of and means for applying liquid to yarns or threads and relates more particularly to the provision of means for applying a substantially constant amount of such liquid.

An object of our invention is to supply substantially uniform amounts of modifying liquid to yarn or thread which is moving at different rates of speed. Other objects of this invention will appear from the following detailed description.

When yarn is being wound on to a rotating cone, bobbin or other package mounted on a spindle that is rotating at uniform speed, as such package is built up, its diameter increases, and therefore the linear speed of the yarn progressively increases. When lubricants, dyes or other finishing liquids are applied to such travelling yarn by means of wicks or rollers, the amount of liquid applied to a unit length of yarn is not constant, since such wicks or rollers furnish a constant amount of finishing liquid per unit time, and therefore when the diameter of the package is large and therefore the linear speed of the yarn is great, the amount of finishing liquid applied per unit length of yarn is much less than is the case when the diameter of the package is small. Because of this, the yarn so treated does not have the same physical properties throughout its length, with the result that fabrics formed therefrom do not have uniform appearance and do not knit uniformly.

We have found method and means for applying substantially constant amounts of finishing liquid to yarns or threads that are being wound at an increasing linear speed.

In accordance with our invention, we apply substantially uniform amounts of a finishing liquid to yarns, threads or filaments that are travelling at an increasing rate by causing the same to move over a finishing liquid furnishing surface that increases with the rate of linear speed of the same.

This invention is applicable to the treatment of yarns, threads, filaments, bristles, straw and other materials of substantially continuous length. These materials may be made of any suitable substance such as cotton, natural silk, wool, reconstituted cellulose, but this invention is particularly applicable to materials made of organic derivatives of cellulose such as organic esters of cellulose and cellulose ethers. Examples of organic esters of cellulose are cellulose acetate, cellulose formate, cellulose propionate and cellulose butyrate, while examples of cellu-

lose ethers are ethyl cellulose, methyl cellulose and benzyl cellulose.

The liquid furnishing means is conveniently in the form of a rotating cone, the lower portion of which is submerged in a bath of the 5 finish. When the yarn is travelling at a lower rate of speed, such as when the diameter of the rotating package upon which it is being wound is small, the yarn is caused to pass over a part of the smaller diameter of the cone, and as the 10 speed of the yarn increases, it is caused to pass over portions of parts of progressively increasing diameters of the cone. This can be accomplished conveniently by causing the yarn to pass through guides in a device which is caused to 15 move towards the larger diameter of the cone as the diameter of the yarn package increases.

The conical roller may be made of any suitable material, such as steel, but we have found that if its surface is made of steel or other metal, 20 the film of liquid tends to fall away into irregular patches, thus preventing even application of the liquid. We therefore prefer to employ a cone having a surface of cork, wood, felt or other relatively porous surface. The cone may be 25 made of steel or other metal covered with a layer of cork or other porous substances, or the cone may be made entirely of wood, or it may be in the form of a wooden cone covered with a layer of cork or the like.

Any suitable finishing or modifying liquid may 30 be applied. Thus the liquid may be a lubricant or finish, which for the treatment of cellulose acetate yarn, may contain polyhydric alcohols or their ethers, such as diethylene glycol, glycol, 35 glycerine, mono ethyl ether of ethylene glycol and the like as described in the application of W. Whitehead No. 365,572, filed May 23, 1929. Such finish may contain in addition to the polyhydric alcohols or their ethers, an oil, such as 40 olive oil, castor oil, or other vegetable, animal or mineral lubricating oils, as described in the U. S. application of F. J. Williams and H. E. Martin No. 349,896, filed March 25, 1929. Further, for the treatment of cellulose acetate, such lubricant or conditioning liquid may contain ethyl oxybutyrate or other relatively non-volatile solvents or restricted solvents of cellulose acetate which is readily removable by water with or without such polyhydric alcohols or ethers, as 50 described in the U. S. application of C. Dreyfus and G. R. Blake, No. 536,310, filed May 9, 1931.

The finishing liquid applied may contain dyes or other material capable of effecting a color change. Such liquid may contain other sub- 55

stances having a modifying effect, such as sodium hydroxide or other alkalies for causing the partial or complete saponification of cellulose acetate yarn. Sizes may be also applied by the present invention.

In order to illustrate our invention, but without being limited thereto, reference is had to the accompanying drawing showing one mode of carrying out our invention, wherein

10 Fig. 1 is a front elevation of the device,
Fig. 2 is a horizontal section along the line 2—2 of Fig. 1, and

15 Fig. 3 is a vertical section along the line 3—3 of Fig. 1.

15 A trough 1 is provided containing a bath of finish, which may compromise an oil, softening agent, lubricant or other conditioning liquid, or it may be a solution of dye or other substance capable of effecting a color change, or any other desired modifying liquid. Over this trough 1, 20 there is mounted a conical roller 2 fixed on the rotatable shaft 3. This roller may be made of any of the materials above described.

25 A spanner 4 is mounted over the conical roller 2, and carries yarn guides 5 and 6 formed in or mounted on the respective arms thereof. One arm 7 of the spanner is fastened by means of the lock screw 8 to the member 9 which is slidably mounted on any suitable support such as the 30 side of the trough 1. By this arrangement, the spanner 4 may be set at any suitable angle with respect to the axis of the cone 2, so that the yarn may be caused to pass at right angles to the axis of the cone when a minimum amount of finish is 35 to be applied, or at a progressively diminishing angle to the axis of the cone when larger amounts of finish are to be applied. The set screw 8 permits the spanner 4 to be fixed at any desired angle.

40 A bobbin 10 supplies the yarn A to be wound and treated. The yarn passes through the gate tension device 11, through the guide 5 on the spanner 4 over the cone 2 and through the other guide 6 on the spanner, to the winding device 12. 45 This winding device is shown as a cone winder, but it may be a device for winding any package such for instance as a bobbin, whose diameter progressively increases as the yarn is wound thereon. The yarn A is led on to the package 50 by means of a guide in an arm 13 of a lever pivoted at 14, the other arm 15 of which carries a weight 16, which causes the arm 13 to press against the periphery of the yarn package 17. It will be seen that as the package 17 is built 55 up, the arm 15 is caused to move laterally.

60 A rod 18 connects the arm 15 with the spanner support 9 and causes the spanner supported thereby to move laterally in the same manner as the arm 15 is caused to move when the diameter 65 of the yarn package 17 increases. In Fig. 1, the solid lines indicate the positions of the parts when the package is small, while the dotted lines indicate the position of the parts when the package is large, the position of the spanner being indicated as 4', the arm of the lever pressing on the periphery 17' of the package being indicated as 13', the weight as 16', the lower end of the lever as 15' and the connecting rod as 18'.

70 In operation, the yarn A is drawn from the supply bobbin 10 through the tension device 11 over the finish supplying rotating cone 2 between the guides 5 and 6 on the spanner 4 to the winding device 12. At the start when the package 17 is small, the yarn A is caused to pass over the 75 smaller end of the cone 2 and contacts with only

a small portion of such cone, and in some cases makes but little more than tangential contact therewith. The angle of the spanner 4 to the axis of the cone 2 will be set by the set screw 8, depending on the type of yarn being treated, 5 the nature of the conditioning liquid being applied and the type of result required.

As the package 17 builds up, the arm 13 pressing against its periphery will cause the member 15 to move laterally which, through the connecting rod 18 and support 9, causes the spanner 4 to move the guides 5 and 6 progressively towards the end of the cone of larger diameter. This causes the yarn A to make contact with the cone 2 in progressively increasing arcs, and in this manner the increase of linear speed of the yarn A due to the increase of size of the package 17 is compensated by the greater surface of the furnishing cone 2 with which it comes in contact. The slope of the cone 2 selected is such that the 20 increase of length of contact of the yarn with the cone is proportional to the increase of the speed of travel of the yarn so that substantially even or uniform amounts of finish are supplied to the yarn throughout its length. 25

Although only one cone 2 and winding device 12 is shown, it is to be understood that a plurality of such devices may be employed, and generally will be employed as is the common practice in the winding art. 30

Yarns, threads, filaments, bristles, straws and other products when treated in accordance with our invention, have superior properties to similar products treated by prior methods. Thus for instance cellulose acetate yarns, when lubricated 35 or conditioned by this invention, because of the uniformity of the application of lubricant or conditioning agent, have uniform knitting properties so that they may be closely knitted on circular or knitting machines with little or no difficulties due 40 to pin holes, distortions and the like, and require much less supervision during their knitting.

It is to be understood that the foregoing detailed description is given merely by way of illustration and that many variations may be made 45 therein without departing from the spirit of our invention.

Having described our invention, what we desire to secure by Letters Patent is:

1. In a device for applying liquid to yarn, the 50 combination of a winding device for the yarn forming a package of increasing size, a container for finishing liquid, a rotatable cone so mounted that the lower portion thereof is immersed in said finishing liquid, guides for the yarn adapted to 55 move together so as to lead the yarn across the surface of the cone at right angles to the axis of the cone while on the way to the winding device, and means for moving the guides to cause the yarn to contact with greater surfaces of the 60 cone as the size of the package increases.

2. In a device for applying liquid to yarn, the combination of a winding device for the yarn forming a package of increasing size, a container for finishing liquid, a rotatable cone so mounted 65 that the lower portion thereof is immersed in said finishing liquid and having a periphery of a relatively porous material, guides for the yarn adapted to move together so as to lead the yarn across the surface of the cone at right angles to 70 the axis of the cone while on the way to the winding device, and means for moving the guides to cause the yarn to contact with greater surfaces of the cone as the size of the package increases. 75

3. In a device for applying liquid to yarn, the combination of a winding device for the yarn forming a package of increasing size, a container for finishing liquid, a rotatable cone so mounted that the lower portion thereof is immersed in said finishing liquid, guides for the yarn to cause the same to contact with the periphery of the cone while on the way to the winding device, and means for moving the guides 10 towards the larger end of the cone as the size of the package increases.

4. In a device for applying liquid to yarn, the combination of a winding device for the yarn forming a package of increasing size, a container 15 for finishing liquid, a rotatable cone so mounted that the lower portion thereof is immersed in said finishing liquid, guides for the yarn to cause the same to contact with the periphery of the cone while on the way to the winding device, and means pressing on the periphery of the package 20

adapted to move the guides towards the larger end of the cone.

5. A device for applying liquid to yarn, the combination of a winding device for the yarn and forming a package of increasing diameter, 5 a trough for liquid, a rotatable cone mounted over said trough and having the lower portion thereof dipping in the liquid, a device spanning said cone and slidably mounted in the direction of the axis of said cone, yarn guides carried by 10 said spanning device on each side of the cone, a lever having one arm thereof pressing against the yarn package, and a rod connecting the other end of the lever and the spanning device carrying the yarn guides, whereby the spanning device is moved towards the larger end of the cone 15 as the size of the package increases.
